US00D869540S

(12) **United States Design Patent** (10) **Patent No.:** **US D869,540 S**
(45) **Date of Patent:** **** Dec. 10, 2019**

(54) **CAMERA**

(71) Applicant: **Hangzhou Imagic Technology Co., LTD**, Hangzhou (CN)
(72) Inventor: **Kaihua Huang**, Hangzhou (CN)
(73) Assignee: **Hangzhou Imagic Technology Co., LTD**, Hangzhou (CN)

(**) Term: **15 Years**

(21) Appl. No.: **29/628,797**

(22) Filed: **Dec. 7, 2017**

(30) **Foreign Application Priority Data**

Aug. 23, 2017 (CN) 2017 3 0390020
